UNITED STATES PATENT OFFICE.

ASA F. BATCHELDER, OF SCOTIA, NEW YORK, ASSIGNOR TO GENERAL ELECTRIC COMPANY, A CORPORATION OF NEW YORK.

RACK LOCOMOTIVE OR CAR.

Application filed May 31, 1924. Serial No. 716,937.

To all whom it may concern:

Be it known that I, ASA F. BATCHELDER, a citizen of the United States, residing at Scotia, in the county of Schenectady, State 5 of New York, have invented certain new and useful Improvements in Rack Locomotives or Cars, of which the following is a specification.

My invention relates to locomotives or 10 cars for railway systems of the type in which portions of the track are of such a steep gradient that traction by means of adhesion of the wheels on the tracks becomes dangerous or impossible, and in which racks 15 are provided on the grades to provide the necessary additional tractive effort. It relates more particularly to a means for facilitating the meshing of the driving or rack gear of such a locomotive or car with a stationary rack as the locomotive or car passes 20 from a section of the system which is not provided with a rack, on to a section which is provided with a rack.

In such a railway system, the locomotives 25 are fitted with a rack gear which is adapted to engage with a rack arranged parallel to the rails on which the locomotive runs. When approaching an incline fitted with such a rack, it has been customary to start 30 up the auxiliary engine or motor driving the rack gear so that by the time it engages with the rack, it will be rotating with a peripheral speed substantially equal to the relative linear speed of the rack with respect to the 35 locomotive, so that the meshing of the rack gear and the rack will take place without undue shock. In practice, however, it is difficult to effect a meshing of the rack and 40 rack gear in this manner owing to the inability of the operator to control the speed of the rack gear and bring it to the proper speed before the meshing takes place. Failure to obtain a meshing, especially when the 45 weight of the train is great, may result in damage to the rack or rack gear or both.

The object of my invention is to provide means whereby the above difficulty of obtaining a meshing of the rack gear and rack without undue shock is overcome and damage to the parts is effectively avoided.

I accomplish the above object by providing means on the truck which will cooperate with the traction rails upon which the locomotive or car runs to impart rotation to the rack gear and cause it to attain a speed cor-

responding to the relative linear speed of the truck with respect to the rack so that when the rack gear engages the rack, it will be rotating at the proper speed and will therefore roll into mesh with the rack without shock, the means which cooperates with the rails upon which the truck runs being movable into and out of engagement with said rails and so proportioned that the speed of the rack gear before meshing with said racks will be substantially equal to the speed of the said gear after meshing with said rack.

The various features of novelty which characterize my invention are pointed out 70 with particularity in the claims forming a part of this specification. For a better understanding of my invention, reference may be had to the following description taken in connection with the accompanying drawing 75 in which Fig. 1 is a fragmentary side elevation of a truck equipped with means embodying my invention, and Fig. 2 is a fragmentary sectional view along the axial center line of the rack gear supporting shaft.

In the drawing a truck embodying my invention is shown mounted upon traction rails 10 of a railway system. The truck comprises a truck frame 11 and wheels 12 which run upon the rails 10. Frame 11 is provided with rack gears 13 rotatably mounted thereon which are adapted to engage a stationary rack 14 located between the rails 10. The rack gears 13 are connected to and are adapted to be driven by motors 15 which are also mounted on the truck frame 11. When the rack gears 13 are in engagement with the rack 14 and the motors 15 energized, the locomotive will be propelled along the rails 10 through the agency 85 of the rack gears 13 and the rack 14 by the motors 15.

In order to facilitate the meshing of the rack gears 13 with the stationary rack 14 as the locomotive passes over onto a section of 100 the railway system provided with a rack 14, means comprising a shaft 16 having a friction wheel 17 mounted thereon is provided to cooperate with the rails 10 and cause the rack gears 13 to rotate before they engage 105 the stationary rack 14 (see Fig. 2). The friction wheel 17 is so proportioned that the peripheral speed of the rack gears 13 before meshing with the rack 14 will be substantially equal to the relative linear speed of 110

the rack 14. Under these conditions, the rack gears 13 simply roll over into engagement with the rack 14 without any sudden change of speed and thus avoid any undue 5 shock such as would occur if the rack gears 13 were not rotating at a proper speed.

The rack gears 13 are carried by a quill shaft 18 which is supported at its ends in bearings 19 on the truck frame 11. The 10 quill shaft 18 is provided with a spur gear 20 which meshes with a gear 21 mounted upon a shaft 22 journaled in the frame of the motors 15. This shaft also carries a second gear 23 which engages a second spur gear 15 24 on the end of the shaft of motors 15. The gears 20 and 21 form a reduction gear connection between the motors 15 and the quill shaft 18. One end of the quill shaft 18 is provided with a universal joint 25 which 20 connects it to and supports one end of the shaft 16. The shaft 16 extends through the quill shaft 18 and is supported at its other end by a journal box 26 which is carried on trunnions 27 which engage a movable yoke 25 28. This yoke 28 is pivoted at one end to the truck frame 11 and is supported at its other end by a piston rod 29 of a pneumatic cylinder 30. The piston rod 29 is biased by spring 31 to a position which will maintain 30 the journal box 26 and the yoke 28 in their uppermost position. In this position, the second shaft 16 will be in a position concentric with the quill shaft 18 and the friction wheel 17 will be held out of contact with the 35 rails 10. The piston rod 29 is connected to a piston (not shown) which moves vertically in the pneumatic cylinder 30 and when sufficient compressed air or other medium is admitted to the cylinder 30 to overcome the 40 bias affected by the spring 31, the shaft 16 will be moved downwardly and the friction wheel 17 will be brought into frictional engagement with one of the rails as shown in Fig. 2 of the drawing. The friction wheel 45 17 may be fitted with a peripheral band of material having a high coefficient of friction to thus improve the grip between the friction wheel 17 and the rail 10.

While I have hereinbefore stated that the 50 friction wheel 17, when in engagement with the rails 10 will impart a rotary movement to the rack gear 13 and the motor 15, it may be found desirable to apply a small amount of electrical energy to the motors 15 and then rely on the friction wheel 17 to control the speed of the motors 15 by either causing them to run faster or slower than they would run without the friction wheel 17 in cooperation with the rails 10.

60 In operation, the operator upon approaching a section of the system provided with a rack 14 applies a reduced voltage to the motor 15 and also operates mechanism adapted to bring the friction wheel 17 into 65 contact with the track rail 10 to thereby

control the speed of the rack gear 13 and the motor 15 and cause them to rotate at the proper speed to secure a meshing without shock. The above operation is performed by the operator at a distance sufficiently in 70 advance of the rack 14 to insure that the rack gears 13 and the motor 15 will be rotating at the proper speed when the rack is engaged. After the meshing of the rack gear 13 and the rack 14 has occurred, the 75 above mechanism is again operated and the friction wheel 17 will then return to its initial position concentric with the axis of the quill shaft 18 and out of engagement with the rail 10.

What I claim as new and desire to secure by Letters Patent of the United States, is:—

1. In a rack locomotive, the combination of a rack gear rotatably mounted upon said locomotive and adapted to engage a stationary rack, and a friction wheel mounted upon said locomotive adapted to cooperate with one of the rails upon which said locomotive runs for causing said rack gear to rotate as the locomotive moves over the rails.

2. In a rack locomotive, the combination of a rack gear rotatably mounted upon said locomotive and adapted to engage a stationary rack, and means comprising a shaft connected to said rack gear having a friction wheel mounted thereon adapted to cooperate with one of the rails upon which said locomotive runs for causing said rack gear to rotate as the locomotive moves over the rails.

3. In a rack locomotive, the combination of a rack gear rotatably mounted upon said locomotive and adapted to engage a stationary rack, a motor on said locomotive adapted to drive said rack gear, and means connected with said rack gear adapted to cooperate frictionally with one of the rails upon which said locomotive runs for controlling the speed of said rack gear and said motor as the locomotive moves over the rails.

4. In a rack locomotive, the combination of a rack gear rotatably mounted upon said locomotive and adapted to engage a stationary rack, a motor on said locomotive adapted to drive said rack gear, and a friction wheel mounted upon said locomotive adapted to cooperate with one of the rails upon which the locomotive runs for causing said rack gear and said motor to rotate as said locomotive moves over the rails.

5. In a rack locomotive, the combination of a rack gear rotatably mounted upon said locomotive and adapted to engage a stationary rack, a quill shaft for supporting said rack gear, and means extending through said quill shaft and cooperating with one of the rails upon which the locomotive runs for causing said rack gear to rotate as the locomotive moves over the rails.

6. In a rack locomotive, the combination of a rack gear rotatably mounted upon said locomotive and adapted to engage a stationary rack, a quill shaft for supporting said 5 rack gear, a second shaft extending through said quill shaft, and a friction wheel secured to said second shaft adapted to cooperate with one of the rails upon which the locomotive runs for causing said rack gear to 10 rotate as the locomotive moves over the rails.

7. In a rack locomotive, the combination of a rack gear rotatably mounted upon said locomotive and adapted to engage a stationary 15 rack, a quill shaft for supporting said rack gear, a second shaft extending through said quill shaft and secured at one end thereto, a friction wheel at the other end of said second shaft, and means for moving 20 said friction wheel into and out of engagement with one of the rails upon which the locomotive runs for causing said rack gear to rotate as the locomotive moves over the rails.

8. In a rack locomotive, the combination of a rack gear rotatably mounted upon said locomotive and adapted to engage a stationary rack, a quill shaft for supporting said rack gear, a second shaft extending through 30 said quill shaft and secured at one end thereto, a friction wheel at the other end of said shaft, adapted to engage one of the rails upon which the locomotive runs, a means for biasing said friction wheel into an inoperative position, and means for overcoming said 35 bias and moving said friction wheel into engagement with the rail for causing said rack gear to rotate as the locomotive moves over the rails.

9. In a rack locomotive, the combination of a rack gear rotatably mounted upon said locomotive and adapted to engage a stationary rack, a quill shaft for supporting said rack locomotive, a second shaft extending through said quill shaft, a universal joint 45 between said quill shaft and one end of said second shaft, a friction wheel mounted upon the other end of said second shaft, and means for moving said friction wheel into and out of engagement with one of the rails 50 upon which said locomotive runs.

10. In a rack locomotive, the combination of a motor upon said locomotive, a quill shaft journaled at its ends to said locomotive and adapted to be driven by said motor, a 55 rack gear secured to said quill shaft and adapted to engage said stationary rack, and means connected to said quill shaft adapted to cooperate with one of the rails upon which said locomotive runs for causing said rack 60 gear and said motor to rotate as said locomotive moves over the rails.

11. In a rack locomotive, the combination of a motor upon said locomotive, a quill shaft journaled at its ends to said locomotive and adapted to be driven by said motor, a rack gear secured to said quill shaft and adapted to engage a stationary rack, and means comprising a second shaft extending 65 through said quill shaft having a friction wheel at the end thereof adapted to cooperate with one of the rails upon which the locomotive runs for causing said rack gear and said motor to rotate as said locomotive 70 moves over the rails. 75

In witness whereof, I have hereunto set my hand this 29th day of May, 1924.

ASA F. BATCHELDER.
